UNITED STATES PATENT OFFICE.

LEO GRUBMAN, OF NEW YORK, N. Y., ASSIGNOR TO ELECTRIC SPARK APPLIANCE CO. INC., OF NEW YORK, N. Y., A CORPORATION OF NEW YORK.

ELECTROMAGNETIC SOUND-PRODUCER.

1,147,016.

Specification of Letters Patent. Patented July 20, 1915.

Application filed June 11, 1914. Serial No. 844,401.

To all whom it may concern:

Be it known that I, LEO GRUBMAN, a citizen of the United States, and a resident of the borough of Brooklyn, county of Kings, 5 city and State of New York, have invented certain new and useful Improvements in Electromagnetic Sound-Producers, of which the following is a specification.

My improvements relate to the class of 10 sound producing devices in which an elastic resilient diaphragm, or sound-wave vibrator, is actuated by electro-magnetic means, usually in conjunction with an armature interposed between the electro-magnet 15 and said elastic resilient diaphragm, the pulsations of the armature being transmitted to the said diaphragm through the medium of various instrumentalities. In all such cases, so far as I am aware, the hammer or 20 armature has been positioned between the magnet and the diaphragm, and the diaphragm has derived its motion from the armature.

In the present case I position the diaphragm between the magnet and the armature or hammer, and the latter derives its motion from the diaphragm, this being one of the distinctive features of the invention.

Another is the provision of means for 30 regulating the tone of the diaphragm by controlling the motion of the armature or hammer, all as hereinafter more fully described and for purposes set forth.

In the accompanying drawings, Figure 1, 35 is a rear view of, say, an automobile horn made in accordance with my present invention; Fig. 2, a central sectional elevation upon plane of line 2—2 Fig. 1; Fig. 3, a sectional detail upon plane of line 3—3 40 Fig. 1.

The construction and arrangement of parts shown in the drawings is designed more particularly for use where an alternating electric current is available, as for 45 instance on "Ford" automobiles, or elsewhere, where transformation of current is unnecessary. That is to say the usual and well known "make and break" means, or "interrupter", used in connection with elec- 50 tro-magnetic horns supplied with continuous electric current is omitted, although such device may be added when necessary without materially altering the construction and arrangement of parts, or the principle 55 of action involved herein. Thus, if my

present invention is to be embodied in a horn operated by means of a continuous current of electricity, the "interrupter" mechanism shown and described in either of my concurrent applications No. 825,114, filed 60 Mar. 16th, 1914, or No. 840,431, filed May 23d, 1914, may be added to the sound producing mechanism herein disclosed with but slight modification of either, if any at all,— it being immaterial in so far as my present 35 invention is concerned, how the alternating current fed to the coil C, is attained.

The omission of "interrupter" mechanism of course enables me to simplify and cheapen the construction of an automobile 70 horn, or similar alarm device, very materially, although this is only an incidental feature in connection with the present invention, one distinctive feature of which is the interposition of the diaphragm D, between 75 the electro-magnet M, and the hammer H, and this whether the latter acts as an armature or not. That is to say, the hammer H, may or may not be formed of magnetic material, while the diaphragm D, is formed of 80 magnetic material and is acted upon directly by the electro-magnet M. The latter consists by preference of a circular plate m, formed with an inturned center or hollow core m', an annular spacing block m², and a 85 disk m³, with a central aperture m⁴, all said parts m, m', m², and m³, being made of magnetic material. The electric coil C, is situated between the magnetic plates m, m³, and surrounds the hollow core m', and it 90 is connected in electric circuit by means well known and not necessary to show or describe herein. The hollow core m', extends to and through the central aperture m⁴, in the disk m³, its inturned edge being 95 flush with the rear face of the latter, as shown in Fig. 2. A spacing washer d, or equivalent, is interposed between the dia- 100 phragm D, and the magnetic plate m³; and the armature or hammer carrying spring h, is mounted on a spacing block h', which is by preference made annular so as to form also a bearing or support for the bracket b, upon which the tuning screws t, t', are mounted. t², is a nut lock plate for secur- 105 ing the tuning screw t, in a predescribed position. These parts are all inclosed in a casing A, and held thereto on one side by anchor screw bolts a', a', passing through the front plate a, of the casing A, the mag- 110

net members m , m^2 , m^3 , the spacing washer d , the edge of the diaphragm D, the block h' , and the spring h —and on the other side by anchor bolts a^2 , a^2 , passing through the 5 front plate of the casing, the magnetic members m , m^2 , m^3 , the spacing washer d , the edge of the diaphragm D, the block h' , rise block b' , and bracket b , both sets of screw bolts a' , a' , and a^2 , a^2 , being secured in place 10 by nuts a^3 , a^3 .

A horn e , is attached to the frontal member a , of the casing A, opening therethrough into coincidence axially with the hollow core m' , of the electro-magnet M, as shown in 15 Fig. 1, so as to receive and transmit the air pulsations created by the diaphragm in action. The casing A, may be left open at the back to be closed by the part to which the instrument may be attached, (as by means 20 of the flange a^3), to the dash board or other fixed part of a Ford machine, to which for its simplicity, cheapness, and adaptability to a variable alternating electric current my device is particularly suited, although applicable for use generally for alarm or 25 sound warning purposes.

The alternating current is transmitted to the coils C, through the medium of binding nuts i , i , and screws i' , i' , mounted on the 30 bracket b , and insulated therefrom as shown in Fig. 3.

It is well known that it is difficult to construct an automobile horn that will respond uniformly or satisfactorily to the varying 35 frequency of an alternating current not produced and regulated by an "interrupter" or make and break device, but derived for instance from the uncertain and changeable speed of an alternating current auto-mag- 40 neto, largely because the weight of the armature is not mechanically responsive to currents of high frequency. Furthermore, as heretofore arranged, the diaphragm has derived its motion from the armature, and the 45 latter, owing to its weight, has not always been responsive to the fluctuations of an alternating current, especially one of high frequencies. If to obviate this, armatures of very light weight are used they lack the 50 requisite power of impact with the diaphragm to insure volume and tone. I obviate this difficulty mainly by interposing the elastic resilient magnetic diaphragm between the electro-magnet and the hammer, which lat- 55 ter need not necessarily be of magnetic material in this arrangement, and hence need not act as an armature. In fact I reverse the order of arrangement and operation by making the diaphragm impart motion to the 60 hammer. Improvement results from the fact that the diaphragm will always respond to all frequencies of magnetic attraction,—the mechanical vibration of the diaphragm being assured irrespective of variable elec- 65 trical conditions. The vibrations thus posi-

tively and directly produced in the dia- 70 phragm by the magnetic pulsations not necessarily being sufficient to afford the requisite loudness or volume of sound, are mainly utilized by me to effect the vibra- 75 tion of the hammer, be the latter magnetic or non-magnetic. As a result dynamic power is imparted to and accumulated by the slower moving hammer, which reacts on the diaphragm with sufficient force to intensify, 80 augment, and accentuate the resultant tone or volume of sound. In effect the hammer thus used becomes a tone-strengthening device, or intensifier, in contra-distinction to the old use of the armature as a tone producer 85 *per se*. When the hammer is magnetic the dynamic energy imparted thereto is augmented by the magnetic influence, but it still derives its main impetus from contact- 90 ing with the diaphragm. In this connection it may be noted that either the diaphragm D, or the hammer H, (or both) is preferably provided with a contact protuberance p , as may be preferred, for the purpose of lim- 95 iting and centralizing the point of contact between said parts.

The vibrations of the hammer being rela- 95 tively slower than those of the diaphragm, as above indicated, it is desirable to insure synchronous concordance of contact and vi- 100 bration between the two, and for this reason I furnish the adjustable tuning screw t , by means of which the scope of vibration of the retractile spring h , may be restricted or am- plified as may be found necessary to bring 105 the hammer and diaphragm into average uniformity of accord. The screw t , is locked in the prescribed position by any suitable means, as by the nut plate t^2 , and pinching screw t' , as will be understood by reference 110 particularly to Fig. 2.

It will thus be seen that my invention in- 110 volves not only a new combination and ar- rangement of parts, but a new method of operation also, *i. e.* the imparting of motion to the hammer through the medium of the diaphragm, and the reaction of the ham- 115 mer against the diaphragm as an intensifier as hereinbefore set forth,—the hammer in such case by its acquired dynamic force and inertia amplifying and accentuating the re- sultant tone and volume of sound thus pro- 120 duced by the magnetic pulsations. The method also of attaining harmonious syn- chronism between the diaphragm and the heavier and slower moving hammer by regu- 125 lating the area or scope of vibration of the latter I also believe to be original with myself, and of special value in connection with the use of alternating electric currents of variable frequency as herein set forth.

What I claim as my invention and desire to secure by Letters Patent is,

1. In electro-magnetic sound producers of 130 the character designated, in combination,

an electro-magnet, a retractile armature, and an elastic resilient diaphragm movable independent of said armature and interposed between said magnet and armature, for the purpose described.

5 2. In electro-magnetic sound producers of the character designated, in combination, an electro-magnet, a retractile hammer, and an elastic resilient diaphragm movable independent of said armature and interposed between said magnet and armature, for the purpose described.

10 3. In electro-magnet sound producers of the character designated, in combination, an electro-magnet, a retractile hammer, an elastic resilient diaphragm positioned between said magnet and said hammer to receive direct impact from the latter, and means for controlling the tone of the diaphragm by 15 regulating the scope of vibration of the hammer, for the purpose described.

20 4. In electro-magnetic sound producers of the character designated, in combination, an electro-magnet, a hammer mounted on a flat retractile spring, an elastic resilient diaphragm positioned between said magnet and said hammer to receive direct impact from the latter, and means for controlling the tone of said diaphragm by regulating the 25 scope of vibration of said hammer and retractile spring, for the purpose described.

30 5. In electro-magnetic sound producers of the character designated, in combination, an electro-magnet, a retractile armature, an elastic resilient diaphragm positioned between said magnet and said armature, and means for controlling the tone of the diaphragm by regulating the scope of vibration of said retractile armature, for the 35 purpose described.

40 6. In electro-magnetic sound producers of the character designated, in combination, an electro-magnet, an armature mounted on a flat retractile spring, an elastic resilient diaphragm positioned between said magnet and said armature, and means for controlling the tone of said diaphragm by regulating the scope of vibration of said armature and retractile spring, for the purpose described.

50 7. In electro-magnetic sound producers of the character designated, in combination, an electro-magnet, a hammer mounted on a flat retractile spring, an elastic resilient diaphragm positioned between said electro-55 magnet and said retractile hammer to receive direct impact from the latter, and an adjustable screw positioned to limit the scope of vibration of said retractile spring and hammer, for the purpose described.

60 8. In electro-magnetic sound producers of the character designated, in combination, an electro-magnet, a hammer mounted on a flat retractile spring, an elastic resilient diaphragm positioned between said electro-65 magnet and said retractile hammer to re-

ceive direct impact from the latter, an adjustable screw positioned to limit the scope of vibration of said retractile spring and hammer, and means for locking said adjusting screw in a prescribed position.

70

9. In electro-magnetic sound producers of the character designated, in combination, an electro-magnet, a hammer mounted on a flat retractile spring, an elastic resilient diaphragm positioned between said electro-magnet and said retractile hammer, an adjustable screw positioned to limit the scope of vibration of said retractile spring and hammer, means for locking said adjusting screw in a prescribed position, consisting of 75 a lock nut plate and binding screw for clamping said lock nut plate, for the purpose set forth.

80

10. In electro-magnetic sound producers of the character designated, an electro-magnet comprising a magnetic plate formed with an inturned central hollow core flange, an annular ring of magnetic material supported upon said plate, a magnetic disk supported upon said ring and formed with a 85 central opening concentric to said hollow core, and an electric coil positioned within the magnet thus constituted and concentric to the hollow core, in combination with a retractile hammer and an elastic resilient diaphragm positioned between said magnet and hammer to be actuated by said electro-magnet, for the purpose described.

90

11. In electro-magnetic sound producers of the character designated, an electro-magnet comprising a magnetic plate formed with an inturned central hollow core flange, an annular spacing ring of magnetic material supported upon said plate, a magnetic disk supported upon said ring and formed with a central opening concentric to said hollow core and through which the latter extends, and an electric coil positioned within the magnet thus constituted and concentric to the hollow core, and with an elastic resilient diaphragm and an armature positioned to be actuated by said electro-magnet, said diaphragm being independent of the armature and disposed between the latter and the magnet to receive direct impact of said armature.

100

12. In electro-magnetic sound producers of the character designated, an electro-magnet comprising a magnetic plate formed with an inturned central hollow core flange, an annular spacing ring of magnetic material supported upon said plate, a magnetic disk supported upon said ring and formed with a central opening concentric to said hollow core and through which the latter extends, and an electric coil positioned within the magnet thus constituted and concentric to the hollow core, and with an armature positioned to be actuated by said magnet, and a diaphragm independent 120 125 130

of said armature and interposed between the same and the magnet to receive the direct impact of said armature.

13. In electro-magnetic sound producers of the character designated, an electro-magnet comprising a magnetic plate formed with an inturned central hollow core flange, an annular spacing ring of magnetic material, and a magnetic disk formed with a central opening concentric to the said hollow core, in combination with an elastic resilient diaphragm positioned upon one

side of the electro-magnet and with a horn positioned upon the other side of said electro-magnet in axial alinement with, and 15 opening into, the hollow core of said electro-magnet and a hammer upon the side of the diaphragm opposite said electro-magnet for the purpose described.
